GREASE GUARD FOR LOOMS

William H. Fowler, East Marion, N. C.

Application July 16, 1942, Serial No. 451,147

2 Claims. (Cl. 139—147)

This invention relates to grease guards and more especially to a device for receiving the grease which drops from the pick cam of a loom.

In textile weaving rooms it is very important that the floors be kept as free as possible from any foreign matter which might damage the yarn, because yarn packages or bobbins often fall upon the floor and roll from place to place. If the package contacts lubricant while upon the floor the yarn therein is usually so damaged that it cannot be used for weaving purposes. One of the most common sources of lubricant droppings from a loom is the pick cam. This cam and associated roller must be frequently greased and therefore, a surplus amount is likely to be applied which drops to the floor.

It is an object of the invention to provide a grease guard which is designed to be removably supported beneath the pick cams of a loom for catching any surplus oil or grease which might fall from the cam.

It is another object of this invention to provide a grease guard of the class described in combination with means for removably mounting the same upon a loom frame and a spring pressed device for releasably holding the guard in mounted position.

Some of the objects of the invention having been stated, other objects will appear as the description proceeds when taken in connection with the accompanying drawing in which:

Figure 1 is an elevation of the lower portion of a loom showing my improved grease guards associated with the loom frame and pick cams;

Figure 2 is a transverse vertical sectional view, taken along the line 2—2 in Figure 1, illustrating the position of one of the grease guards relative to one of the loom pick cams;

Figure 3 is a vertical sectional view, taken along the line 3—3 in Figure 1, showing the relative position of another grease guard to the remaining pick cam of the loom;

Figure 4 is an elevation, similar to the upper central portion of Figure 1, but showing a slightly modified form of grease guard in association with the loom pick cam and loom frame;

Figure 5 is a transverse vertical sectional view taken along the line 5—5 in Figure 4;

Figure 6 is a sectional plan view taken along the line 6—6 in Figure 5.

Referring more particularly to the drawing, the numerals 10 and 11 denote spaced loom frames which support rocker shaft 12 and cam shaft 14. The rocker shaft has conventional picker stick shoe support 15 on each end there-

of, said support serving as a bearing for picker stick shoe 16, which shoe supports picker stick 17. A lug strap 18 has one end thereof encircling the picker stick 17 and its other end connected to a pick cam lever 19. This lever is pivoted intermediate its ends as at 21 and has a roller 22 on its upper end. The roller 22 is adapted to engage the periphery of a pick cam 23 which is fixedly mounted upon shaft 14.

Generally, there are two pick cams 23 for each loom, these cams being identical in construction except opposite hand to each other. During the normal operation of the loom, the shaft 14 and cams 23 are rotated by any suitable means, not shown, and this rotation will cause levers 19 to oscillate about points 21 while the rollers 22 ride upon the peripheries of the cams. The oscillation of the lever 19 will cause the picker stick 17 to rock back and forth from left to right in a conventional manner.

The pressure and the wear between the roller 22 and pick cam 23 is very great at times, therefore, it is very essential that the parts be properly lubricated. The cam 23 is usually lubricated by applying the lubricant directly to its periphery. There is usually other means for lubricating the cam roller 22. After continued use, the lubricant upon members 22 and 23 becomes worn and thin, thereby increasing the tendency to cause the lubricant to drop therefrom, and as heretofore stated, when this lubricant falls upon the floor, it is likely to damage packages or bobbins of yarn which fall thereon from time to time.

As a means for preventing this worn lubricant from falling upon the floor, I have provided a grease guard 25 directly below one of the pick cams 23. This grease guard is U-shaped when looking at the right hand face thereof in Figure 1, and is also U-shaped in cross section. In other words, the grease guard comprises a U-shaped bottom 26 (see Figure 2) which has integral with opposed sides thereof upturned flanges 27 and 28. The top edges of these flanges are adapted to be positioned low enough so the same will clear the high side of pick cam 23 when the grease guard is removed from installed position. These flanges 27 and 28 project above bottom 26 sufficiently high to retain a substantial amount of worn grease or lubricant which might fall from the cam 23.

As a means for removably securing the grease guard 25 to the loom frames 10 suitable open-ended slots 29 are provided in flange 27. A stud bolt 30 is adapted to penetrate each of these

slots, the smaller ends of said stud bolts being threadably secured in the loom frame 10. These slots permit the elevation of the guard 25 to be varied and also permit the guard to be entirely removed for cleansing purposes by loosening bolts 30.

The remaining pick cam 23, which is shown in the right-hand portion of Figure 1 and also in Figure 3, has another type of grease guard 32 disposed thereunder. This grease guard is of a slightly different shape but constructed along the same general lines. On account of a warp follower shaft 33 and a bearing 34 being disposed directly beneath the remaining pick cam 23, it is necessary to flatten the bottom of the guard 32 sufficiently to clear the bearing. This bearing 34 has a flange 34a which extends upwardly above shaft 33 and alongside the inner face of frame 11, thereby making it necessary to indent the sidewalls of grease guard 32 as at 35 to conform to this flange.

The grease guard 32 likewise has a bottom 36 which is U-shaped when viewed in Figure 3 and which is also U-shaped in the cross section. The guard also has upturned flanges 37 and 38 integral with each side of the bottom so that the guard will serve as a pan or container.

As a means for removably supporting guard 32 upon the loom frame 11 suitable slots 39 are provided in flange 38 and a stud bolt 40 is adapted to penetrate each of said slots 39 and to have the inner end thereof threadably secured in frame 11. These slots 39 and bolts 40 permit the height of the guard to be varied, as well as permit the guard to be removed for cleansing purposes when desired.

Figures 4, 5, and 6 show a slightly modified form of the invention. It is here seen that a grease guard 45 is provided beneath the pick cam 23. This guard has a bottom 46 which is U-shaped when viewed as in Figure 5 and which is also U-shaped in cross section. The bottom 46 has upstanding flanges 47 integral with each side thereof in which two pairs of alined holes 49 are provided. Each pair of alined holes are adapted to removably fit over a pin 50 which extends inwardly from the loom frame 10.

As a means for releasably holding the guard 45 upon the pins 50, a suitable projection 51 is provided upon each side of the guard 45. Each 50

projection is adapted to penetrate a hole 52 in a leaf spring 53, said leaf spring being secured to the loom frame 10 as at 54. Since the upper edges of the flanges 47 will always clear the high side of cam 23 the guard 45 may be moved horizontally away from the loom frame 10 when the leaf springs 53 are sprung outwardly sufficiently to allow projections 51 to be released from holes 52.

- 10 When it is desired to insert the grease guard 47 again upon the pins 50, it is only necessary to place the holes 49 around pins 50 and then let the projections 51 spread the leaf springs 53 when the out-turned proximate faces of these 15 springs are contacted. Upon the projections reaching holes 52, the springs 53 will snap against the opposed outer side wall of the grease guard to releasably lock the guard upon the pins and to the loom frame.
- 20 In the drawing and specification, there has been set forth a preferred embodiment of the invention, and although specific terms are employed, they are used in a generic and descriptive sense only and not for purposes of limitation, the scope of the invention being set forth 25 in the following claims.

I claim:

1. In combination with a loom frame having a cam shaft and a pick cam on said shaft, a grease guard disposed below said cam, said guard being U-shaped when looking at the face of said cam and also being U-shaped in cross section, horizontally projecting pins extending from said frame for removably supporting said guard, and spring means for releasably holding said guard on said pins.
2. In combination with a loom frame having a cam shaft and a pick cam on said shaft, a grease pan disposed below said cam, said pan having a bottom and opposed end walls and sidewalls of lesser height than the end walls, said end walls extending upward along opposed edges of the sidewalls in the form of inturned flanges, said flanges being provided with alined holes, a pair of pins extending from the loom frame through said holes, said sidewalls having projections on their outer surfaces and spring means for engaging the projections to hold the grease pan on said pins.

WILLIAM H. FOWLER.
